DEVICE FOR WINDING TUBULAR OR
CAN COPSHans Schweiter, Horgen, near Zurich,
SwitzerlandApplication May 24, 1933, Serial No. 672,692
In Germany August 1, 1932

4 Claims. (Cl. 242—27)

My invention relates to a device for winding tubular or can cops which comprises an axially fixed revolving spindle stump over the free end of which the cop continuously is stripped off continuously by the yarn which is fed onto it. Winding devices of this type, when compared with the known devices fitted with an axially reciprocating spindle, afford the advantage of eliminating the soiling of the material to be wound, which is unavoidable with reciprocating spindles. Furthermore the drawback is overcome which occurs in winding comparatively long cops by means of these known devices, of the cop being withdrawn from the spindle only with difficulty. However, 10 winding devices fitted with the axially immovable spindle stumps suffer from the drawback that, especially in winding comparatively long cops or cops of comparatively fine yarn material, bending of the cop cannot be avoided, so that 15 such long or fine cops can be made only on winding machines having vertical spindles, the attendance of which machines, however, is very complicated.

Supports for the free ends of the spindles have 20 been used in winding machines having horizontally disposed spindles for the purpose of preventing the bending of the cops. However, this expedient has not produced the desired results because, in view of the normal length of cops, a 25 bending nevertheless takes place. It has been found that a speed of the spindle beyond 600 or 300 R. P. M. is not practical because of the destructive effects of the centrifugal force upon the spools, which render them unmarketable. An 35 other disadvantage presents itself in the arrangement using counter-supports for the spindles which limits the speed of operation. In the use of fine materials, the rubbing resulting from the threads against the counter-support causes a 40 burning thereof and at high speeds is sufficient to destroy the material.

The use of a long spindle with a uniform cross section has proven impractical for the reason 45 that the pressure, resulting from the several thousand turns of elastic yarn material wound upon the growing spool, which is exerted upon the spindle prevents a sliding of the spool upon the spindle. The use of a long conically shaped spindle does not solve the problem. Thus, when the 50 spindle is tapered but slightly, the same relations exist as those explained above for a cylindrical spindle of uniform cross section in which the yarn material at winding is tensioned and, on account of its elasticity, it adheres to the spindle even 55 though the latter decreases in size. If the spindle

is steeply tapered, then the same disadvantages arise as when a spindle stump is used. At a definite point of the spindle surface, the contraction of the inside of the spool ceases and becomes loosened from the spindle core. The cop is then 60 no longer centered and is influenced by the centrifugal forces arising from the high speeds of operation, 3000 to 4000 R. P. M. The cop disposes itself eccentrically to the spindle and develops a strong centrifugal force which is capable of 65 damaging the apparatus and the spindle. Aside from the possible damage to the machinery, the texture of the cop becomes loose and thereby unusable.

The object of the invention is to provide a 70 guide for the spindle stump which on the one hand prevents a throwing of the cop and on the other hand affects the pressure relations in such a manner that an easy stripping of the spool from the spindle guide is possible. The desired 75 object is attained by providing a suitable prismatic or cylindrical extension of smaller cross section than the spindle stump upon the latter. The cross section of this smaller spindle portion is so chosen that it is adapted to the contracted 80 opening of the spool after the latter is stripped from the main spindle stump, which contraction arises from the elasticity of the yarn material. Likewise, the cross section of the extension is so chosen that the movement of the spool thereon 85 is not hindered and, on the other hand, no more play than is absolutely necessary for this movement is provided in order to prevent a centrifugal throwing of the cop. Thereby one is enabled to use winding machines of conventional construction 90 having horizontally disposed spindles operating at speeds of 3000 to 4000 R. P. M. without fearing that the cops will bend and tear apart and with assurance that the growing cop is capable of movement along the spindle, and the 95 removal thereof by hand after it is finished may be effected easily and without hindrance.

In order that my invention may be clearly understood and readily carried into effect, an embodiment thereof is illustrated by way of example in the accompanying drawing in which

Fig. 1 is a side elevation of one of the spindle units, showing a spool core in section, at the beginning of the winding operation,

Fig. 2 is a side elevation corresponding to Fig. 105 1 and showing the winding of the spool in an advanced stage,

Fig. 3 is a side elevation of a spindle unit showing the spool in its finished condition preparatory to its withdrawal from the spindle, and

Fig. 4 is a side elevation corresponding to Fig. 3, showing the simple withdrawal of the spool from the spindle guide.

Referring to these figures, 9 denotes a casing which encloses a gearing as commonly used with cop winding machines and by which a reciprocating motion is imparted to the yarn guide 10. The gearing is driven by friction discs 11 and actuates a shaft 12 mounted in the casing 9. The other end of shaft 12 is formed with a spindle stump 13 of prismatic cross section. A bevel roller 14 is revolvably mounted on a shaft 15 in a carrier 16 below the spindle stump 13, and acts as a feeler. The spindle stump 13 carries an axial spindle extension 17 of prismatic or circular cross section but of somewhat smaller diameter than the former. Only a rotary movement is imparted to the spindle unit by the driving mechanism.

The winding operation is the same as with the known winding devices of this type. In order to facilitate the starting cone of the cop, especially in winding fine yarns, a hollow auxiliary core 24 is used which is put on to the spindle stump 13, the yarn being clamped between these two parts. Thereupon the device is set in motion, with the yarn guide depositing yarn layer on to yarn layer always on the same place and with uniform reciprocating stroke. During this operation, the feeler roller 14 comes to act from the beginning and owing to its being mounted stationarily causes a continuous outward shifting of the cop as it is formed, thus stripping off of the cop from the spindle stump 13.

The cop is supported during the winding operation by the extension 17 of smaller diameter over which the growing cop gradually and loosely is shifted. After the cop 25 has been formed in this manner, it can simply be removed by hand, as illustrated in Figures 3 and 4. This removal does not offer any difficulty even with very long cops as only a small portion of the cop is carried by the spindle stump 13, whereas the extension 17

of smaller cross section serves only as a loose guide from which the finished cop can easily be removed.

What I claim as my invention is:

1. In a machine for winding tubular cops, an axially stationary and rotatable spindle consisting of a main portion and an extension on said main portion, means for winding yarn upon the main portion of the spindle and means at said main portion for shifting the wound cop along said spindle, said extension having a substantially uniform cross section slightly smaller than that of the main portion to permit an effective guiding and easy shifting of the cop along the spindle. 80

2. In a machine for winding tubular cops, an axially stationary and rotatable spindle consisting of a main portion and an extension on said main portion, means for winding yarn upon the main portion of the spindle and means at said main portion for shifting the wound cop along said spindle, said extension having a substantially uniform cross section of the same contour as the main portion and slightly smaller than the cross section of the main portion to permit an effective guiding and easy shifting of the cop along the 90 spindle. 95

3. In a machine for winding tubular cops, a rotary spindle consisting of a main winding portion and an extension on said main portion having a substantially uniform cross section slightly 105 less than that of the main portion to permit an effective guiding and an easy movement of the cop along the spindle. 100

4. In a machine for winding tubular cops, a rotary spindle consisting of a main winding portion 110 and an extension on said main portion having a substantially uniform cross section of the same contour as the main portion and slightly less than the cross section of the main portion to permit an effective guiding and an easy movement of the 115 cop along the spindle. 115

HANS SCHWEITER.
